UNITED STATES PATENT OFFICE.

EDWARD ERMOLD, OF NEW YORK, N. Y.

BOTTLE-LABELING MACHINE.

No. 893,317.

Specification of Letters Patent.

Patented July 14, 1908.

Application filed September 27, 1907. Serial No. 394,855.

To all whom it may concern:

Be it known that I, EDWARD ERMOLD, a citizen of the United States, residing in New York, in the borough of Manhattan, county 5 and State of New York, have invented certain new and useful Improvements in Bottle-Labeling Machines, of which the following is a specification.

This invention relates to certain improvements in bottle-labeling machines of that class in which horizontally - reciprocating pickers, which are supplied with paste on their faces, take up a label which is supplied and transmit the same over the bottle and apply it to the same by the pressure of elastic wipers passing over the ends of the label; and the invention consists more specifically in improvements in the bottle-labeling machine for which Letters Patent were granted 20 to me on September 5, 1899, No. 632,519. In the prior patent referred to, the label was applied to the lower part of the bottle and only one shape and size of bottles could be labeled by the machine. This was found 25 inconvenient as it confined the machine to special shapes and sizes.

The object of the present improvement is to paste the label on to the upper part of the bottle while permitting the labeling of any 30 size or shape of bottles, round, flat or otherwise. For this arrangement the label-feeding devices have to be placed in a position above a horizontal plane passing through the center of the bottle, whereby the construction of the machine is considerably 35 simplified, and its operation facilitated, and in which the bottle is always within sight while being labeled.

For this purpose the invention consists of 40 a machine for labeling bottles, which comprises horizontally-reciprocating pickers that take up the paste and transfer it to the edges of the label, means for carrying forward the pickers with the label for applying it to the 45 bottle in connection with a vertically-reciprocating plunger, oscillating wipers, means for moving the wipers laterally and holding them in lateral position for permitting the return of the wipers and removal of 50 the labeled bottle.

The invention consists further of certain details in the construction of the machine, and more specifically in the arrangement of the label-feeding device above the reciprocating pickers, instead of below the same, and in the specific construction of the paste-

supply and label-feeding mechanism, as will be fully described hereinafter and finally pointed out in the claims.

In the accompanying drawings, Figure 1 60 represents a front-elevation of my improved bottle-labeling machine, Fig. 2 is a side-elevation of the same, Fig. 3 is a plan-view, partly in horizontal section, on line 3, 3, Fig. 2, Fig. 4 is a vertical longitudinal section of the operative parts of the machine on line 4, 4, Fig. 3, drawn on a larger scale, Fig. 5 is a horizontal section on line 5, 5, Fig. 4, showing the cam-shaft with its cams for transmitting motion to the 70 different parts of the machine, Fig. 6 is a detail front-view of the oscillating wipers showing the mechanism for holding the same in laterally-spread position for clearing the bottle after the label is applied thereto, 75 Figs. 7, 8 and 9 are respectively a detail front-elevation, a plan-view, and a vertical section on line 9, 9, of Fig. 8, of the picker-mechanism by which the paste is transferred to the opposite ends of the label. Figs. 80 10, 11 and 12 are respectively a detail plan-view, a vertical transverse section on line 11, 11, Fig. 10, and a sectional side-elevation of the label-feeding device. Fig. 13 is a detail vertical central section of the fol- 85 lower used in the label-feeding device. Fig. 14 is a detail plan-view, partly in horizontal section, of the paste-box and the paste-transfer roller. Fig. 15 is a side-elevation of Fig. 14, and Figs. 16 and 17 are 90 respectively a detail section and a side-view of the bottle-holding plunger.

Similar letters of reference indicate corresponding parts throughout the different figures of the drawings.

Referring to the drawings, A, A¹ represent the upright standards of the supporting-frame of the improved bottle-labeling machine. On the lower part of the standards are arranged the journal-bearings for the 100 driving-shaft S and the cam-shaft S¹, to which latter power is transmitted from the driving-shaft by gear-wheels h, h¹. On the upper part of the supporting-frame are arranged the horizontally-reciprocating picker-carriage B, the vertically - reciprocating plunger D, the paste-feeding-mechanism, the label-feeding devices and the oscillating wipers.

The main-parts of the improved bottle-labeling machine consist of the vertically-reciprocating plunger D, by which the bottle

is held on a stationary bottle-rest G after the label to which paste has been supplied, is transferred thereto, pickers P which are supported on the horizontally-reciprocating picker-carriage B, and laterally-oscillating and spring-actuated wipers F sidewise of the bottle by which the ends of the pasted label are applied to the bottle. The parts referred to are located approximately in a vertical plane, one below the other, when the label is applied to the bottle. Back of the wipers is arranged the label-feeding device E, and back of the latter is located the stationary paste-supply mechanism C. The horizontally-reciprocating picker-carriage B is guided in horizontal ways w of the supporting-frame and operated by a suitable lever-mechanism from a cam on the cam-shaft S¹. Rotary motion is transmitted from the driving-shaft S to the cam-shaft S¹, the driving-shaft being provided in the usual manner with a fast and loose pulley and a belt-shifting mechanism so as to receive power from an overhead shaft. The pickers are arranged parallel with each other at the front-part of the picker-carriage, and are operated in such a manner that during the forward motion of the picker-carriage the faces of the pickers are supplied with paste by means of a paste-transfer roller r, after which the pickers are raised so as to take up the lowermost label from the label-feeding device, then lowered again and moved forward into line with the plunger and bottle-rest, upon which the label is transferred by the descending plunger onto the upper part of the bottle, and then applied by the action of the oscillating wipers to the bottle.

The actuating mechanism of the paste-transfer roller, vertically-reciprocating plunger, label-feeding device, and oscillating wipers is so timed that as soon as the label is transferred from the pickers to the bottle, the picker-carriage and pickers are moved in backward direction clear of the label-feeding device, while during the forward motion the faces of the pickers receive a new supply of paste from the paste transfer-roller, pick up a new label, and transfer the same to the next bottle, and so on.

The picker mechanism.—The picker-mechanism is shown in side-elevation in Fig. 4 and in detail in Figs. 7, 8 and 9. It consists of the picker-carriage B which is guided in the ways w and depressed at its middle-portion and provided with upright stops b. At the center of the picker-carriage B is arranged a socket b¹ for the shank b² of a base-plate b³ of the picker-frame. The ends of the base-plate b³ are provided with upright arms b⁴, to the upper ends of which are attached by means of screw-bolts, inclined arms b⁵ which carry at their upper ends the horizontal pickers P. The picker-faces may be round or oval when round or oval labels are to be

used, and oblong when square or oblong labels are to be used for the bottles. Adjacent to and near the middle of each picker-face is arranged a transverse slot b⁶ which permits the pickers to rise over the lower ends of the label-holding fingers of the label-feeding device, so that the paste-covered picker-faces can pick up the lowermost label in the label-feeding device and transfer the same in forward direction over the bottle. The base-plate b³ of the pickers is rigidly attached to the upper shouldered end of the shank b² by means of a clamping screw-nut b⁸ by which the picker-frame proper is firmly connected with the shank b². The upright picker-supporting arms b⁴ are provided at their inner sides with lateral strengthening ribs which are made integral with the same. From the rear of the socket b¹ extends in upward direction a curved arm b⁹, which is connected at its upper end by means of a pivot-link b¹⁰ with an oscillating lever-arm b¹¹ that is mounted on an auxiliary shaft S² supported in bearings of the side standards of the supporting-frame, said lever-arm having at its lower part a forwardly-extending lug b¹² which is connected to a forked pivot-arm b¹³ provided with an antifriction-roller b¹⁴ that moves over the surface of a cam b¹⁵ on the cam-shaft, so as to impart oscillating motion to the lever-arm b¹¹ and by the intermediate lever-mechanism reciprocating motion to the picker-carriage. When the pickers arrive below the label-feeding device, a vertical motion is imparted to the pickers by a lever-arm b¹⁶ that is also mounted on the rock-shaft S², and provided at its front-end with a curved heel b¹⁷ which engages the lower end of the picker-shank b². The lever-arm b¹⁶ has an antifriction-roller b¹⁸ which is engaged by a double cam b¹⁹, so as to give a quick upward motion to the picker-frame and bring the pickers in contact with the lowermost label of the label-feeding device.

Before the lifting action of the picker-frame takes place, the picker-faces are supplied with paste by an oscillating paste-transfer roller r, the shaft r⁶ of which is engaged by the lower forked ends of two lever-arms r¹ which are mounted at their upper ends on a rock-shaft S³, which is supported in bearings at the upper part of the supporting-frame, said rock-shaft receiving motion by a lever-arm r² which is keyed to the rock-shaft S³ and connected by a rod r³, that is forked at its lower end, with the cam-shaft S¹, said connecting rod being provided with means for adjusting the same as to length, and with an antifriction-roller r⁴ that moves over a cam r⁵ on the cam-shaft S¹, and thereby transmits rocking motion to the rock-shaft and oscillating motion to the paste-transfer roller r. The transfer-roller r is made of sufficient width so as to cover both picker-faces. On the shaft r⁶ of the transfer-roller r is arranged

a pinion r^7 which engages a gear-wheel r^8 on the shaft r^9 of the fountain-roller r^{10} , said shaft turning in bearings of the paste-box C^1 . The fountain-roller r^{10} is partly submerged in the paste in the paste-box C^1 and the paste taken up by the same regulated by a pivoted and weighted doctor-blade r^{11} which is held in position by a set-screw r^{12} . Continuous rotary motion is imparted to the fountain-roller r^{10} in the paste-box by a chain-and-sprocket-wheel transmission r^{14} from the driving-shaft S , the sprocket-wheel r^x being located on the shaft of the fountain-roller and driving an intermediate gear-wheel r^{13} which meshes with the gear-wheel r^8 on the shaft of the fountain-roller. The pinion r^7 on the shaft of the paste transfer roller r is placed in mesh with the gear-wheel r^8 on the shaft of the fountain-roller when the transfer-roller is moved in backward direction over the paste-supply mechanism, so that the transfer-roller is placed in contact with the fountain-roller, whereby a new and uniform supply of paste is transferred to the transfer-roller. The paste-box C^1 is supported on a bracket at the rear-part of the supporting-frame. The shaft of the transfer-roller is guided in parallel ways r^{15} , which are arranged on the supporting-standards, as shown clearly in Figs. 3, 4 and 14. The transfer-roller r transmits the paste to the picker-faces during its forward motion, so that they are coated with a film of paste. As soon as this is accomplished, the upward motion of the pickers towards the label-feeding device takes place, so that the picker-faces are placed in contact with the lowermost label and pick the same on the descending motion of the pickers.

The label-feeding device.—The label-feeding device E is shown in section in Fig. 4 and in detail in Figs. 10, 11, 12 and 13. It is located at the upper center portion of the supporting-frame and composed of two semi-circular shells e, e , which are attached to transverse bars e^1, e^2 , of which the front-bar e^1 is attached to parallel horizontal rods e^3 , while the rear-bar e^2 is adjustable and secured at one end by a sleeve e^4 and set-screw e^5 to one of the horizontal supporting-rods e^3 . The shells e are attached by means of bosses and fastening-screws to the horizontal bars e^1, e^2 . By the adjustment of the cross-bar e^2 towards or away from the cross-bar e^1 labels of different sizes can be placed into the shells. At the lower center-portions of the semi-circular shells e are arranged lugs e^6 on which the pile of labels is supported. At both sides of the shells are arranged fingers e^7 having inwardly-bent pointed lower ends e^8 which engage the lowermost label of the pile. The fingers e^7 are attached at their upper ends to horizontal arms e^9 which are guided by means of clips e^{10} on transverse guide-rods e^{11} , each clip being provided with an angular rack-bar e^{12} which meshes with a center-

pinion e^{13} . The center pinion e^{13} can be turned by a hand-wheel e^{14} on the rear-end of its shaft, that is supported in a cross-bar e^{16} , for the purpose of setting the fingers away from each other when the machine is not required for use, so as to permit the refilling of the label-feeding device with a new pile of labels or towards each other so that their points engage the lowermost label of the pile. The transverse bar e^{16} is guided in vertical ways e^{17} of the supporting-frame and provided with inclined lugs e^{18} at its lower edge, which engage with correspondingly-inclined lugs e^{19} on a laterally-movable bar e^{20} that is guided at one end in a recess of the supporting-frame and connected at the opposite end by a pin e^{21} with the slotted end of a crank-arm e^{22} that turns in lugs e^{23} of the supporting-frame, as shown in Figs. 1 and 11, the shaft of the crank-arm e^{22} being actuated by a hand-lever e^{24} at the front-end of the machine by which the transverse bar is moved so as to raise thereby the inclined lugs, the cross-bar e^{16} and the parts supported thereon above the pickers, whenever the feeding of the labels from the label-feeding-device E is to be interrupted. The transverse supporting-bar e^{16} , the fingers e^7 and the shells with the labels are all raised at the same time, so that the entire label mechanism is raised out of contact with the pickers, and thereby placed out of operation. Above the pile of labels in the shells is arranged a weighted follower i , which is shown in Figs. 2 and 13 and which is suspended from a collar i^1 at the lower end of a vertical-rod i^2 the upper end i^3 of which is toothed in the nature of a rack-bar and engaged by a weighted pawl i^4 that is pivoted to a stationary lug i^5 at the upper part of the supporting-frame, as shown in Fig. 2, the weighted pawl being provided with a tooth i^6 that permits the locking of the follower i in raised position when the same is lifted out of the label-feeding device so as to give access to the latter for placing a new pile of labels therein. The follower i is made tubular and provided with an interior shoulder i^7 on which rests a helical spring i^8 which bears by its upper end against a collar i^9 on the rack-bar i^3 so that the follower exerts a yielding pressure on the pile of labels in the shells. When the pawl is in normally dropped position, it enters automatically tooth by tooth into the rack-bar and holds thereby the gradually diminishing pile of labels under uniform pressure in the shells e, e , of the label-feeding device so as to secure the reliable and uniform feeding of the labels, one after the other, to the pickers.

The plunger.—The plunger D is arranged at the upper front-part of the machine and its shank d guided in keepers d^1 arranged at the center of a cross-bar d^2 of the supporting-frame. The plunger D is shown in detail in Figs. 16 and 17. Vertically-reciprocating

motion is imparted to the plunger D at the proper time by means of a fulcrumed lever d^3 , which engages the upper end of the plunger-shank d . The rear-end of the lever d^3 is connected with a pivot-rod d^4 having a forked lower end that rides on the cam-shaft S^1 and carries an antifriction-roller d^5 which moves over a cam d^6 on the cam-shaft S^1 . The underside of the plunger D is made concave or flat, according as round or flat bottles are to be labeled. The face of the plunger D is covered by a layer of felt, rubber or other suitable soft material so as to soften the impact of the plunger with the bottle. The plunger D is pivoted to the lower end of a spring-actuated rod d^7 which is guided in the socket-shaped lower end of the shank of the plunger and which has a certain vertical play in the slotted lower end of the shank d by means of a cross-pin d^8 which is retained in the slotted end by a collar d^9 and set-screw d^{10} as shown in Figs. 16 and 17. The plunger D is cushioned by a spring d^{11} which is interposed between the shank and rod d^7 and yields in upward direction and by its pivot-connection with the rod d^7 in forward and backward direction so as to be capable of use for holding any shape or size of bottle to be labeled.

30 The wipers.—Below the plunger D and in the same vertical plane therewith are arranged two oscillating wipers F, which are shown in Fig. 1 and in detail in Figs. 5 and 6. The wipers F are inserted into the recessed ends of wiper-levers f which are fulcrumed to the upper ends of upright arms f^1 that are pivoted at their lower ends to lugs f^2 of a U-shaped transverse bar f^3 which is supported on the front-end of a lever f^6 that is applied at its rear-end to the rock-shaft S^2 . The lever f^6 has an antifriction-roller f^x which is engaged by a cam f^9 on the cam-shaft S^1 . The wiper-levers f are connected at their outer ends with elbow-levers f^7 , which are fulcrumed to upright lugs f^8 of a stationary transverse bar f^9 , the lower arms of the elbow-levers being connected by helical springs f^{10} with a transverse rod of the supporting-frame. The tension of the springs f^{10} presses the elbow-levers f^7 against short cam-levers f^{11} which are fulcrumed to the upper ends of the stationary lugs f^8 and which are connected by curved pivot-links f^{12} with a lever f^{13} fulcrumed at f^{13a} and operated by a cam f^{14} on the cam-shaft S^1 , said cam being in contact with an antifriction-roller f^{15} at the side of the fulcrumed lever f^{13} . The actuation of the fulcrumed lever f^{13} by the cam produces the lifting of the cam-levers f^{11} and imparts a lateral motion to the wiper-levers and wipers, so that the latter are removed sidewise of the bottle and permits them to be returned into raised position without forming contact with the bottle and interfering with the label just placed thereon. The wipers are made of

elastic material, such as soft rubber, so that they can readily pass over the ends of the label and over the sides of the bottle by the downwardly-oscillating motion imparted to them by their actuating mechanism. The label is applied to the bottle by the pressure of the wipers in the usual manner, after which they are spread apart by the pivoted cam-levers f^{11} for clearing the bottles as described. Below the wipers is arranged a stationary bottle-rest G, which is supported at the upper end of an adjustable support g, the lower end of which is attached to the stationary arm of the transverse bar f^9 described. The bottle-rest G is provided at its rear-end with a stop g^1 which is adjusted for the length of the bottle by a set-screw g^2 and against which the bottle is pressed by the attendant, as shown in Fig. 4. The bottle-rest G is made in different shapes, according as it is to be used for labeling round, quart or pint bottles or flat whisky-flasks, or other bottles, a special bottle-rest being preferably used for each size and shape of bottle. The bottle-rest is located vertically below the plunger and serves to support the bottles for the action of the wipers after the label has been transferred to the bottle by the pickers.

Operation.—At the lower front-part of the machine is arranged the foot-treadle T, which operates by a connecting-rod t a clutch-mechanism T^1 by which the cam-shaft S^1 is thrown into gear with the driving-shaft S, and thereby the machine started. During the return-motion of the picker-carriage the faces of the pickers are supplied with paste by the oscillating transfer-roller, which takes up the paste from the paste-roller in the paste-box and transfers it to the faces of the pickers. When the picker-faces have received the paste, they are raised by the action of the raising mechanism towards the label-feeding device so as to take up the lowermost label in the same, the lower ends of the label-holding fingers passing through the slots in the picker-arms. After the label is picked up by the pickers, the latter are lowered again. The pickers are then moved forward so that the label is placed over the bottle. The plunger D then descends and presses the label onto the upper part of the bottle, which is held against the gage-plate by one hand of the attendant. The wipers are then actuated so as to press the pasted ends of the label on the bottle and apply them thereto by the hugging action of the wipers, which imitate the action of the fingers of the hand in applying labels to a bottle. While the wipers are passed over the bottle, the pickers are lowered and moved in backward direction. The labeled bottle is removed by the attendant and another bottle placed on the bottle-rest against the gage-plate of the same, the picker-carriage and plunger being in the meantime returned to

their starting positions. During the backward motion of the picker-carriage, the plunger moves upward, while during the forward motion of the picker-carriage the pickers receive a new supply of paste and take up a new label, so that when the pickers are returned in line with the bottle-rest, the next label is applied to the bottle by the wipers and so on. The attendant places the bottles in position alternately with the right and left hands, each actuation of the labeling-machine labeling the bottle, which is held at the neck and removed after the label is applied. By arranging the label feeding device at the upper part of the machine, the feeding of the labels and the actuation of the machine are greatly simplified, with the advantage that by the placing of the labels on the upper part of the bottles the labeling operation can be better observed by the attendant.

While the bottle-labeling machine covered by my prior patent referred to was mainly designed for the use of large beer-bottling establishments, the improved construction is designed for labeling Rhine-wine, claret and champagne, quart and pints, also for labeling whisky-bottles and flasks, and other bottles. The range of the work is thereby greatly increased and the bottle-labeling machine better adapted to the different requirements of the beer, wine and whisky trade.

Having thus described my invention, I claim as new and desire to secure by Letters Patent:

35 1. In a bottle-labeling machine, the combination, with a bottle-rest and a horizontally reciprocating carriage carrying pickers, of a paste-box above the carriage having a paste-roller therein, a transfer-roller guided horizontally above said carriage, and arranged to transfer the paste from said paste-roller to the pickers, and means for actuating said transfer-roller.

2. In a bottle-labeling machine, the combination, with a bottle-rest and a horizontally reciprocating carriage carrying pickers, of a paste-box above the path of the picker-carriage, a transfer-roller to transfer the paste from the paste-box to the pickers, ways in which said transfer-roller is guided, levers having forked ends fitting over the shaft of said transfer-roller, and means for oscillating said levers.

3. In a bottle-labeling machine, a label-feeding device comprising horizontal rods, bars fitting over said rods at the ends of the former, one of said bars being adjustable toward and away from the other, and coöperating label-holding shells carried by said bars.

60 4. In a bottle-labeling machine, a label-feeding device comprising a label-holding receptacle, fingers projecting beneath the same at opposite sides, rods on which said fingers are supported, and a rack mechanism by

which said rods are simultaneously moved toward or away from each other.

5. In a bottle-labeling machine, the combination of a vertically guided cross-bar having inclined surfaces at its lower edge, a label-feeding device supported on said cross-bar, a horizontally movable bar having inclined surfaces to coöperate with those of the cross-bar and thereby raise or lower the latter, and means for operating said horizontally movable bar.

6. In a bottle-labeling machine, the combination of a stationary bottle-rest, a vertically-reciprocating plunger above said bottle-rest, a horizontally-reciprocating picker-carriage, vertically-reciprocating pickers guided in said carriage, a stationary paste-box, an oscillating paste-transfer roller, means for passing the paste-transfer roller over the pickers, a label-feeding device above the level of the bottle-rest, and oscillating and spring-actuated wipers located sidewise of the bottle-rest.

7. In a bottle-labeling machine, the combination of a stationary bottle-rest, a vertically-reciprocating plunger, a picker-carriage, ways for guiding said picker-carriage, vertically-reciprocating pickers guided in said picker-carriage, means for reciprocating the picker-carriage, means for raising and lowering the pickers at the proper time, a stationary paste-box provided with a paste-roller, a transfer roller rotating in contact with the paste-roller for receiving the paste, means for oscillating said paste-roller for transferring paste to the faces of the raised pickers, means for feeding one label after the other to the pickers while they are in raised position, and oscillating and spring-actuated wipers located sidewise of the bottle-rest.

8. In a bottle-labeling machine, the combination of a supporting-frame having horizontal ways, a horizontally-reciprocating picker-carriage guided in said ways, vertically-reciprocating pickers guided in said picker-carriage, a stationary paste-box, a paste-roller in said box, means for imparting rotary motion to said paste-roller, a paste-transfer roller guided in ways of the supporting-frame, means for rotating said transfer-roller when in contact with the paste-roller, means for imparting oscillating motion to said transfer-roller for transmitting the paste to the faces of the pickers, and means for delivering one label after the other to the pickers at each upward motion of the same.

9. In a bottle-labeling machine, the combination of a horizontally-reciprocating picker-carriage guided in ways of the supporting-frame, a picker-frame supported on said carriage, said picker-frame being provided with upright standards, upright stops on the carriage for the picker-frame, picker-carrying arms attached to the upper ends of

the picker-frame, means for imparting a vertically-reciprocating motion to the picker-frame, a paste-box, means for transferring paste from said box to the faces of the pickers when the picker-carriage arrives at the end of its reciprocating motion, a label-feeding device located above the pickers and provided with label-retaining fingers, the picker-arms being provided with slots for permitting the passing of the fingers through said slots when the pickers are raised for taking up the lowermost label from the label-feeding device.

10. In a bottle-labeling machine, a label-feeding device consisting of two semicircular shells, a stationary shell and an adjustable shell, each shell being provided with an inwardly projecting bottom-lug for supporting a pile of labels placed in the same, fingers for supporting the lowermost label, arms for supporting said fingers, a spring-actuated follower pressing on the pile of labels in the shells, and means for permitting the gradual downward motion of the follower.

25 11. In a bottle-labeling machine, a label-feeding device consisting of two semicircular

shells, a stationary front-shell and an adjustable rear-shell, projecting lugs at the lower ends of the shells, inwardly-projecting fingers supported between said shells, a 30 spring-actuated plunger, means for feeding the plunger into the shells, means for lifting the plunger out of the shells and supporting it in raised position, and means for raising the shells from their normal position so as to 35 insert a pile of labels in the same.

12. In a bottle-labeling machine, the combination with the wipers, wiper-levers and means for oscillating the same, of fulcrumed and spring-actuated elbow-levers connected 40 with said wiper-levers, and oscillating cams engaging said elbow-levers and moving said wipers in lateral direction for cleaning the bottle on the return-motion of the wipers.

In testimony, that I claim the foregoing as 45 my invention, I have signed my name in presence of two subscribing witnesses.

EDWARD ERMOLD.
